CONTAINER

Filed Dec. 26, 1928

54 Inventor John George,
By Wilkinson, Shirley, Byron & King &
Attoys.

UNITED STATES PATENT OFFICE

JOHN GEORGE, OF CHICAGO, ILLINOIS

CONTAINER

Application filed December 26, 1928. Serial No. 328,554.

This invention relates to containers and the like and is disclosed herein as embodied in a novel canteen or flask suitable for holding and dispensing liquids.

5 As shown in the drawings—

Fig. 1 is a plan view looking down upon the top of the improved canteen,

Fig. 2 is a view in front elevation looking toward the improved canteen,

10 Fig. 3 is a side elevation showing the canteen of Fig. 2 with the straps removed,

Fig. 4 is an enlarged view in section of the improved canteen, and

15 Fig. 5 is a view in side elevation in section of the canteen shown in Fig. 4.

As illustrated, the body of the canteen or flask comprises an annular drum 10 and oppositely disposed sides 12 and 14. The drum is made up of a series of transversely extending panels or sections of wood, and all of such sections are grooved as indicated by the reference numerals 16 to form a recess for the reception of the side panels 12. In assembling the canteen the side sections 12 are placed within the grooves 16 and metal encircling bands 18 are tightly applied to the outer exposed edges of the drum sections 10 to hold the drum and sides in rigid assembled relationship.

20 The interior of the canteen is coated with a suitable substance such as resin or the like to provide an inner covering or coating 20. Under normal conditions the coating is the only part of the canteen in contact with the enclosed fluid, thereby preventing the fluid from being contaminated by contact with exposed portions of the container. Furthermore the surface in the rear of the coating is made up entirely of wood, in view of which 25 feature of construction the fluid is prevented from coming in contact with metal fastenings or the like, even when the coating is rubbed away or is omitted by intention.

To the end of providing means for filling 30 the canteen, there is provided a wooden spout 22 extending radially from the upper portion of the drum 10, and for purposes of protection and to prevent breakage the wooden spout 22 is enclosed in a metal casing. As 35 illustrated, the latter comprises a base plate

24 having a funnel shaped portion 26 extending upwardly therefrom, terminating in a screw threaded collar 28. An enclosing cap 30 interiorly screw threaded, is adapted to be surmounted upon the funnel shaped member 26 and provides a closure for the spout 22. To prevent the metal of the cap 30 from coming in contact with the enclosed fluid, there may be provided a cork or other washer 32.

40 To the end of dispensing the fluid from the canteen, a second wooden spout 34 is arranged in a manner similar to the filling spout 22 on the opposite side of the center line therefrom. The spout 34 is surrounded by a funnel shaped metal member 36 which is 45 likewise surmounted by a closure cap 38, and located between the end of the wooden spout 34 and the cap 38 is a perforated member 40 for straining the liquid being poured from the flask or canteen. If desired, the strainer 50 may be made of a wooden material, or coated with a non-contaminating fluid, and a washer made of wood or some other suitable material may be inserted in the cap 38 to prevent the liquid from coming in contact with the metal 55 of the cap. On the other hand it will be appreciated that under normal conditions the canteen will be carried in an upright position, in which position it will be impossible 60 for the water or liquid contained to come in contact with the metallic parts.

65 Disposed in between the filling and dispensing spouts is a hollow container comprising a base 42, and a top 44, having screw threaded engagement with one another. Within the hollow container there is disposed a drinking cup 46 and a funnel 48 for use 70 in filling the canteen. This, it will be appreciated, is an extremely compact arrangement and being located between the two filling spouts it occupies an out of the way position.

75 To serve in supporting and carrying the container there are provided for the former purpose a suitable number of supporting legs 50 by means of which the canteen, if placed upon a level surface will be maintained in an upright position. For the latter purpose eye-bolts 52 extend from opposite sides of 80 the drum 10 and have links 54 loosely swiv- 85

eled therein. Attached to the links 54 are segmental straps 56 adapted to be joined by means of buckles 58. These straps serve handily in securing the container in position during use. A person's arms may be inserted through them, or they may be employed in securing the canteen to the parts of an automobile, wagon, etc.

I claim:

10. 1. A canteen comprising, in combination, a drum made in sections, said drum being provided with annular grooves, sectional members closing the ends of the drum, said members being seated in the annular grooves, and metallic means adapted to hold the drum and closure members in assembled relation, the interior of said drum being coated with a non-contaminatable substance.
15. 2. A canteen comprising, in combination, a drum made in sections, said drum being provided with annular grooves, members closing the ends of the drum, said members being seated in the annular grooves, a filling spout secured to said drum, a dispensing spout also secured to said drum but spaced from said filling spout, and a metallic casing secured to said drum and forming housings for said spouts.
20. 3. A canteen comprising, in combination, a drum made of wooden sections, said drum being provided with annular grooves, wooden members closing the ends of the drum, said members being seated in the annular grooves, metal rings adapted to hold the drum and closure members in assembled relation, a filling spout secured to said drum, a dispensing spout also secured to said drum metallic casing secured to said drum and forming housings for said spouts, a container
25. 40. located on said drum intermediate said spouts, said container including a base and a top threaded thereto, and straps secured to said drum forming means for carrying the canteen.
45. 45. Signed at Chicago, Illinois, this 6th day of March, 1930.

JOHN GEORGE.
